UNITED STATES PATENT OFFICE.

JOHN C. WAHL, OF CHICAGO, ILLINOIS, ASSIGNOR TO THE WAHL COMPANY, OF CHICAGO, ILLINOIS, A CORPORATION OF DELAWARE.

MECHANICAL PENCIL.

Application filed April 28, 1922. Serial No. 557,198.

My invention relates to mechanical pencils.

The object of the present invention is to provide a device of the class described which will be simple of construction and operation and contain no involved or intricate parts which would likely break in ordinary usage.

The invention comprehends the relation-
10 ing of a feed mechanism to the pencil body
and to details of construction hereinafter
specifically pointed out and described.

The invention consists in the combina-
tions and arrangements of parts hereinafter
described and claimed.

15 The invention will be best understood by
reference to the accompanying drawings
forming a part of this specification.

Referring to the drawings:

Fig. 1 is a side elevation of my improved
20 pencil, and

Fig. 2 is a longitudinal sectional view of
Fig. 1.

In the drawings, the numeral 10 indicates
25 a barrel being tapered at 11 to form the
tip 12 through which a lead is adapted to
be propelled. In the construction illustrated
an inner sleeve or tube 13 is provided which
extends from the rear end of the barrel 10
30 to the union member 14, said union member
being fashioned with a central longitudinal
bore 33 having an expanded threaded por-
tion 34 at its forward end for union with
the threaded portion of the lead guide, also
35 said union member is conically formed at
its rear end as at 35 for the purpose of cen-
tering the lead with respect to a lead pro-
peller hereinafter mentioned. It will be
seen that the threads of the sleeve or tube 13
40 are rolled thereon the entire length and the
union member 14 is so fashioned as to re-
ceive the threaded sleeve 13.

Referring specially to the operating mech-
anism for propelling a lead through the tip
12, magazines 15 for extra leads are pro-
45 vided, and these magazines are utilized as
an actuating member for moving the follower
or feed wire, hereinafter to be described,
through the lead guide. The magazines are
50 positioned opposite each other, the forward
end being fixedly attached to the magazine
head 16, said magazine head 16 acting
as a plug to prevent the extra leads from
falling out of the magazines, it being also
55 fashioned to form a neck 17 which acts
as a guide for the lead propeller. The

rear ends of the magazines are encircled
by a threaded collar 18 which is fixedly
attached thereto and acts to hold them in po-
sition, the threads of said collar being adapt-
ed to receive the threads of the sleeve 19
60 which frictionally engages the cap 20. At
the open or free end of the sleeve 19 are in-
turned flanges 21 which form grips for
the sleeve.

The collar 31 located at the rear end of
the threaded sleeve or tube 13, the outer cir-
cumference of which is dimensioned to con-
form with the inner face of the barrel 10,
is permanently attached by soldering, or
any other desired manner, to the inner face
70 or wall of the barrel or casing 10, and the
sleeve 13 may be fixed with relation to the
barrel 10 either by being fixedly connected to
the collar 31, or by having frictional engage-
ment with the interior of the barrel as de-
75 sired.

The mechanism constituting the follower
which forces the lead out from the end of
the pencil through the tip 12, consists of a
member 23 in the nature of a stiff wire
80 which member terminates at its rear end in
an enlarged head 24 which constitutes a
cross head. This cross head is formed ex-
teriorly with threaded surfaces which are
85 adapted to engage the threads in the sleeve
or tube 13.

It is obvious, as the cross head is rotated,
by turning the cap 20 in a clockwise direc-
tion, which in turn rotates the magazine, the
cross head will move downward and force
90 the follower or feed rod forward with the
result that the lead is fed out through the
tip of the pencil.

It is thought that the above brief descrip-
tion as to the feeding mechanism for advanc-
ing the lead will suffice as no claims are
made specifically to this construction except
in conjunction with associated parts herein
described; the same is more fully and com-
pletely described in Patent No. 1,130,741
100 granted to Charles R. Keeran under date of
March 9, 1915.

The tip 12 is exteriorly fashioned to provide
a general inclination as indicated at 24 that
is in conformity with the general inclination
of the tapered portion 11 of the barrel 10.
25 indicates the manner of fashioning the ex-
treme end of the tip by an inward deflection
from the general line thereof indicated at
24. 26 indicates a rectilinear shoulder off-
110

set at the rear end of the tip, provided for abutment entry into the end of the tapered portion 11 of the barrel 10 and for snug seating within the interiorly beveled portion 27 thereof.

28 indicates a lead passing through the centrally disposed bore within the tip. 29 refers generally to a tensioning member adapted to be fitted to the inner opening of

- 10 the tip. The tip, per se, illustrated is merely shown in the general outline and no special reference will be made thereto herein-after as it is not included in the improvement herein to which the claims are directed; 15 a more complete description can be found in applicant's pending application dated October 27, 1921, Serial No. 510,813.

31' indicates a lead guide permanently affixed to the tip 12, said lead guide being exteriorly threaded at its upper end to engage the threads 34 in the union member 14.

25 A clip 35', consisting of a prong 36 and a base or supporting portion 37 is provided. The base 37 has a flange 38 swedged thereon, and said flange is adapted to contact with the inside of the tube 10. The thick portion of the base 37 is adapted to fit into a hole 39 which is punched in the barrel 10, and the flange 38 prevents the withdrawing 30 of the clip 35 from the barrel 10.

35 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the 40 appended claims.

Having described my invention, what I claim as new and desire to secure by Letters Patent is:—

45 1. In a mechanical pencil a barrel, a threaded lead propeller, a sleeve having threads cooperable with said propeller, means on said sleeve to limit its advance

toward the tip of the barrel, a tip adapted to seat in the forward end of the barrel, a union member adapted to thread onto the forward end of said sleeve, a lead guide fixed to said tip and adapted to be removably connected with said member to draw said tip and sleeve toward each other to seat them firmly in said pencil. 65

2. In a writing instrument a barrel tapered at one end, an elongated threaded sleeve fixed in said barrel, a union member having screw threaded engagement with the inner end of said sleeve, an internally threaded extension on said union member, a tip having an external taper similar to and continuing the taper of the end of the barrel, and a lead guide fixed at one end to the tip and at its other end having threaded engagement with the internally threaded extension of the union member. 65

3. In a writing instrument a barrel tapered at one end, an elongated threaded sleeve fixed in said barrel, a union member extending into the inner end of said sleeve and fixed thereto, a tip adapted to seat in the tip end of said barrel, and a lead guide fixed to the tip at one end and detachably connected to the union member at the other. 75

4. In a writing instrument a barrel tapered at one end, an elongated threaded sleeve in said barrel, a tip, a lead guide fixed at one end to said tip, a union member detachably and removably connected to said sleeve, one end of said lead guide being detachably connected to said union member. 80

5. In a mechanical writing instrument a barrel, an elongated thin metal sleeve fixed in said barrel, said sleeve having threads pressed therein, a union member having external threads in threaded engagement with the inner end of said sleeve, a tip, and a lead guide fixed at one end to said tip and detachably connected at its other end with said union member. 85

In witness whereof, I have hereunto subscribed my name.

JOHN C. WAHL.
